UNITED STATES PATENT OFFICE

2,368,332

BLOWOUT PREVENTER

Donald U. Shaffer, Brea, Calif.

Application May 10, 1943, Serial No. 486,441

12 Claims. (Cl. 286—16)

This invention has to do with deep well apparatus and particularly deep well drilling and is a blow-out preventer adapted to be installed in the head works of a well casing for practically instantaneous use when evidence of blow-out is given or one may be reasonably expected.

In deep well operations tool strings of various kinds are lowered into and operated in lining casings of a hole and it is highly desirable to have, in the casing works at the head of the hole being drilled, a device which can be quickly actuated to snugly close onto an introduced tool string, for instance drill pipe, to prevent natural pressure of well fluids from blowing out at the head of the well hole. More or less complex means for such prevention have been devised and installed but the initial stock cost and the cost of installation of the device and necessary equipment is, particularly under current conditions of supply and labor, very objectionable.

Therefore an object of the invention is to provide a simple, practical, substantial, low cost and easily installed and reliably operative blow-out preventer. Especially an object is to eliminate as far as possible or to greatly reduce the amount of extraneous apparatus needed for the mere actuation of the principal element of the device.

A further object of the invention is to provide a blow-out preventer which will enable the ready passage of elements of the drilling string, inclusive of the commonly used pipe protector.

A purpose of the invention is to provide a blow-out preventer whose operational parts can be motivated by the mere turning of one element by any suitably motivated, rotary drive connector, of a close up or remote source of power.

The invention consists in certain advancements in the deep well industry as set forth in the ensuing disclosure and having, with the above, additional objects and advantages as hereinafter developed, and whose construction, combinations and details of means, and the manner of operation will be made manifest in the description of the herewith illustrative embodiment; it being understood that modifications, variations and adaptations may be resorted to within the scope, spirit and principle of the invention as it is more particularly claimed in the addendum.

Figure 1 is an axial section of the blow-out preventer.

Figure 2 is a plan of the dissembled running ring of the device, and

Figure 3 is power-side elevation of the unit.

As here shown a substantial vertical barrel 2 has a basal flange 3 to the bottom face of which

5 a subjacent well casing fitting (not shown) is rigidly bolted or otherwise fastened, all in coaxial alinement. Screwed internally in the lower end of the barrel 2 is a bushing 4 on which sets an anti-friction ball bearing 5 on the top of which rotates a worm gear 6 in the form of a flat ring having a plurality of short helical lugs 7 constituting segments of screw threads matching female threads or thread grooves 8 cut in the periphery of a cylindrical thimble 9.

10 The thimble is splined and slidably fits in an internal shoulder 10 of the barrel and in an equi-hored face of the bushing 4. Packing 11 is placed in the bore face of the bushing to seal the intruded body of the thimble 9 and a top packing 12 makes a seal between the top of the running gear 6 and the adjacent, bottom face of the internal barrel shoulder 10.

15 The upper end of the thimble is enlarged to 20 overhang the shoulder 10 and land against the same in a retracted position as effected by the rotation of the running ring gear 6 and the screw action of the lugs 7 in the thread grooves 8 of the thimble. The enlarged upper end of the thimble 25 is provided with an internal, upwardly flared, inverted conic seat 9a on which normally rests the lower, conical end 13 of a stiff but deformable cylindrical choke 14 having an internal bore about equal to that of the thimble 9 so that parts 30 of a made up drill string, and appliances may be lowered down in and pulled from the casing on which this blow-out preventer is mounted. The choke is preferably made of a suitable quality and appropriately firm rubber stock.

35 The upper end of the choke has projecting bolts 15 mounted in a hanger ring 16 landed in the upper, threaded bore 17 of the barrel 2 and held by a lock-bushing 18.

The normal assembled, uncompacted position 40 al relation of the thimble 9 and its superjacent choke 14 is such that there is capacity of a considerable degree of axial upward movement of the thimble toward the lower end of the fixed choke 14. A simple, reliable and powerful means 45 are here provided to effect the axial motion of the thimble 9 at any time that it may be desirable to compress the lower end of the hollow choke 14 and cause it to crowd hard inwardly against the presented outer surface of any tool string part that may at the time be juxtaposed in the choke.

50 A preferred form of actuating means includes a helical pinion or short screw 19 boxed in the side of the barrel and constantly meshing with the companion gear 6. Rotary motion from any

suitable manual or prime motor source is transmitted through a stud shaft 20 of the pinion 19 to turn the latter with the result that the externally thread-grooved thimble 9 will, in one direction move up in the barrel and compact and contract the foot of the choke 14 to make a shut-off of even very high well pressures and prevent a blow-out. By a reverse rotation of the gear 6 the contracted rubber is released to normally expand to free position.

What is claimed is:

1. A blow-out preventer of the class described and including a socketed barrel, a tubular, resilient choke element fitting the socket bore wall and having a contractive, tapered end, a contractor axially shiftable in the socket and engageable with and for contracting the said end upon axial movement of the contractor in one direction in the barrel, and means for axially moving the contractor and means fixed to the barrel and anchoring the choke element against axial shift bodily with or by the contractor.

2. A blow-out preventer having a barrel, a choke fixedly mounted in and peripherally seating on the bore wall of the barrel and bored for passage of a tool part through the barrel and having a contractive end portion, a thimble mounted in the barrel for axial shift to engage and compress and telescope on said end of the choke, and means to actuate the thimble.

3. The preventer of claim 2; the thimble having an external helical groove and said means including a screw part working in the said groove to shift the said thimble axially.

4. The preventer of claim 2; said means including a gear ring mounted in the barrel and through which the thimble extends axially and having an actuating connection with the thimble.

5. A blow-out preventer having a barrel, a thimble axially shiftable in the barrel, a contractive choke member fixedly mounted in the barrel and seated on its bore wall and coaxial with the thimble and having an end seated on

and contractive thereby and forming therewith a passageway for a tool part, a rotative device in the barrel and interengaged with the thimble to axially shift it, and means for rotating the said device; the choke and said element having meeting, conic end faces.

6. The preventer of claim 5; the said device having a screw-effect coaction with the thimble.

7. The preventer of claim 5; said means including a gear and pinion mechanism mounted in the barrel.

8. A blow-out preventer of the class in which there is a normally open passage about a tool part which is axially disposed in the preventer in normal operation of the tool so that there is no normal engagement friction of the said part in the preventer; said preventer embodying a barrel, a removable choke element, fixedly anchored and seating on the barrel wall, and an actuatable thimble telescoping on and contracting one end of the choke upon relative movement in the barrel as to the anchored element.

9. The preventer of claim 8, and means for effecting the telescopic action of the thimble.

10. The preventer of claim 8, the thimble and the choke having engageable end faces of differential conic slope.

11. A blow-out preventer having a barrel, an elastic choke element sealingly fitted in the bore of the barrel and means anchoring the choke against axial shift in the barrel, and a contractor operative in the barrel telescopically engaging and radially contracting one end of the choke when moved therewith.

12. A blow-out preventer having a barrel, an anchored choke element and an axially shiftable thimble fitted in the bore of the barrel; the said element and the thimble having telescoped end portions of differential slope so that the lip of the choke is radially contracted upon initial relative shift action of the thimble as to the element.
